UNITED STATES PATENT OFFICE.

CHARLES A. FERRY, OF NEW HAVEN, CONNECTICUT.

MACHINE FOR EXCAVATING EARTH IN TRENCHES.

SPECIFICATION forming part of Letters Patent No. 253,995, dated February 21, 1882.

Application filed February 12, 1881. (No model.)

To all whom it may concern:

Be it known that I, CHARLES A. FERRY, of New Haven, county of New Haven, Connecticut, have invented a new and useful Machine 5 for Excavating Earth in Trenches, of which the following is a specification and clear description of the same.

This invention consists in certain improvements in machines for excavating earth, which 10 will be hereinafter described, and pointed out in the claims.

In the drawings, Figure 1 represents a side elevation, and Fig. 2 a plan, of my improved machine. Figs. 3 to 10, inclusive, are enlarged 15 detail views of parts of the machine, as hereinafter described. Fig. 11 is a front elevation of the pile-drivers and the pile-driver frames. Fig. 12 is an elevation of the bolt for securing 20 parts of the framing together, with capability of adjustment, as hereinafter described.

C represents the platform or frame-work, of timber, of any suitable size, which is supported on casters h.

D D represent two pile-drivers, which are 25 placed one on each side of the truck, so that both rows of sheeting can be driven at the same time. Each driver has three base-timbers, 1, 1, and 2. The base-timbers 2 slide upon the cross-beam 3 of the main platform C, and are framed 30 and bolted to the two base-timbers 1 1. The two base-timbers 1 1 in the preferred construction, as shown in the drawings, gradually converge toward each other until their rear ends meet. These ends are bolted together at, and 35 and are then pivotally secured to, the cross-sill 4 of the main platform by the pivot-bolt G. The two base-timbers 1 1 are also framed and bolted to the two drivers D. The drivers D are joined at the top by the block 5, which also 40 serves as a support for the pulley. (Not shown.) These five timbers form the essential parts of each of the two driver-frames. The timbers A' and B' serve as braces to stiffen the other parts. So far the drivers are independent, and 45 are each free to move sidewise by the base 2, sliding on the main platform and revolving around the point G. The two drivers are yoked together by means of two planks, F and H', which are secured to the base 1 are secured to the 50 cross-bars E' by the bolts E. Each of these

planks has a slot, s, through which the bolts E pass, so that when the bolts E are loosened the two drivers are free to move laterally independently of each other. The bolt E is shown separately in Fig. 12. 6 is a set-nut, 55 and 7 is a movable nut and washer. The upper part, 8, of the bolt is passed through the cross-bar E', and the set-nut 6 is then screwed up to the cross-bar E'. The yoke F is then put on, and the nut and washer 7 are screwed up 60 firmly against the under side of the yoke, so as to hold it firmly from slipping, the part of the bolt 8 being, however, free to turn in the cross-bar E when desired. The hammer is made very narrow, in order that the guides 65 may support the planks F and prevent them binding from the force of the blow, and thus cause the whole effect of the blow to be given through the center of the planks. When the nuts E' are loosened each driver is free to turn 70 around the bolts at G, or near the center of the frame.

The excavator and elevator consist of two endless chains, H H, carrying between them the buckets I and running over the wheels 75 K L M N, the whole being supported by the frame O, which turns on the trunnions J, and thereby imparts a lateral motion to the lower ends of the guides g and to the wheel K. The frame O being supported on the trunnions J, 80 it is thereby capable of a rotary motion thereon, which will impart to the guides g and the wheel K the lateral motion above referred to. The object of this is that in case the platform should not stand level the guides g would be 85 able to take a perpendicular position without straining any of the parts. It will probably never be necessary for the frame to rotate through more than five or ten degrees. The wheel K is supported by the four guides g, 90 which pass through the frame f, which is free to turn on the shaft of the driving-wheel L. The wheel M is supported in the frame P, which slides in the grooves h in the frame O, and is kept in place by means of a counter-weight 95 attached to the rope r, which passes over the pulley r'. By this arrangement three motions are obtained for the wheel K, viz: first, a lateral motion, by reason of the frame O turning on the trunnions J; second, a longitudinal mo- 100

tion, by reason of the frame *f* revolving on the shaft of the wheel *L*; and, third, a vertical motion, by reason of the guides *g* sliding through the frames *f* and the frame *P* sliding 5 in the frame *O*.

The frame *f* (shown in perspective at Fig. 5) is a rectangular cast-iron frame having a hole, *a*, through which the shaft of the driving-wheel *L* passes, (see Figs. 3 and 4,) and rectangular 10 openings *g' g'*, Fig. 5, through which the guides *g* slide. This frame holds the upper ends of the guides in position, their lower ends being held in a similar frame, in which the wheel *K* turns in a similar manner to that of wheel *L*.

The carrier consists of two endless wire 15 ropes, *R*, which pass over the wheels *S* *T* and support between them, by means of wire hooks *H' H²*, (see Fig. 10,) an endless canvas trough, *U*, Figs. 2, 7, 8. The loop of the hook is made 20 a little larger than the rope, in order that it may be free to slide along it. The wheels *S* and *T* are grooved, so as to hold the ropes, and the teeth *T'* and the depressions between the teeth are intended to allow of the passage 25 of the hooks over the wheels without being cut.

Fig. 10 shows the connection between the canvas carrier on one side only. *R* is the endless rope. *H' H²* represent the hook. *U* is the endless canvas trough, and *L'* is a small cord 30 sewed in the edge of the trough. That part of the hook at *H'* is bent in the form of a circle a little larger than the diameter of the rope, so that it is free to slide along it, as before stated. The carrier is of canvas folded together. The end *H²* of the hook is bent around 35 the edge of the trough within which the cord *L* is sewed.

Fig. 9 is a side elevation of part of one of the wheels, *S* or *T*, a vertical section thereof 40 being incidentally shown in Fig. 10. *W* is the main part of the rim. *T'* is a tooth or cog for holding the rope. *S'* is a shoulder, which raises the rope from the main part *W* of the rim, so that when the machine is in motion, 45 if one of the hooks should strike one of the teeth *T'*, said hook will slide backward or forward on the rope, depending on which side of the tooth it hits, and fall between the shoulders *S'*. By this means the frictional contact of 50 said hook with the rim of the wheel and the rope will be avoided, and the danger of either the rope or the hook being cut by reason of their rubbing against the wheel, which they would do were such shoulders or their equivalents absent, is avoided.

The buckets *I* are formed from a single piece of sheet metal, the corners being cut out and the sides bent up and riveted together. The scraping-edge *i'* is preferably formed out 55 of a separate piece of steel, so as to be easily renewed when worn without necessitating the furnishing of an entirely new bucket.

b represents a strengthening-rib on the bucket, which operates as a stay to prevent its 60 buckling.

c are pivots by which the buckets are connected to the chain.

i are prongs or teeth, which are only used when working grade soil. They may be dispensed with when working sandy soil. They 70 may be arranged at any desired distance apart.

d represents wheels, which act to support the endless chain *H* and prevent its sagging. As many of such wheels may be employed as is found desirable.

e is a brace, Fig. 8, which extends across from one edge of the canvas to the other edge thereof, to keep the trough *U* from buckling or folding together. It may be fastened either directly to the edges of the canvas or to the 80 ropes *R*.

In the operation of the machine the wheel *K* is drawn down into the trench and the buckets are pressed against the bank. The wheel *M* is at the same time drawn forward by the 85 endless chains *H*, which are kept taut by means of the counter-weight attached to the rope *r*. The buckets are filled as they pass under the wheel *K*. They are then drawn up by the driving-wheel *L*, and pass back horizontally to and over the wheel *M*, where the earth is dumped into the endless canvas trough *U*. They then travel forward to and pass over the wheel *N*, and from thence down to the wheel *K*, to be again filled. The endless ropes *R* and trough *U* travel over the 90 wheels *S* and *T*, and the earth is finally dumped.

The excavator and elevator and the carrier may be operated by means of belts passing 100 from a pulley or pulleys connected with a steam-engine or other suitable motive power to other pulleys on the shafts of the wheels *L* and *S*.

k are toothed wheels to aid in keeping the 105 canvas taut and assist its movement forward.

Having thus described my invention, what I claim as new therein is—

1. The combination, with the main frame *C*, of the drivers *D*, bolts *E*, slotted planks *F*, 110 and bolts *G*, substantially as and for the purpose set forth.

2. The combination of the wheels *K L M N*, endless chain *H*, wheel *d*, buckets *I*, and the frame *O*, substantially as and for the purpose 115 set forth.

3. The combination of the frame *O*, trunnions *J*, guides *g*, and frames *f*, constructed and operating substantially as and for the purpose set forth.

4. The buckets *I*, having a separable scraping-edge, *i'*, pivots *c*, strengthening-rib *b*, and prongs *i*, substantially as and for the purposes set forth.

5. The combination of the carrier *R*, consisting of two endless wire ropes, the wheels *S* and *T*, wire hooks *H' H²*, and endless trough *U*, substantially as and for the purpose set forth.

6. The wheels *S* and *T*, having teeth *T'* 130

and shoulders S', as and for the purpose described.

7. The combination of the buckets I, chain H, wheels K and M, drive-wheel L, wheel N, 5 and endless concaved trough U, substantially as and for the purpose set forth.

8. The brace Q, in combination with the canvas trough U, substantially as and for the purpose described.

In testimony whereof I affix my signature in 10 presence of two witnesses.

CHARLES A. FERRY.
